ENGINE GOVERNOR

Anker K. Antonsen, Beloit, Wis., assignor to
 Fairbanks, Morse & Co., Chicago, Ill., a corpora-
 tion of Illinois

Application December 28, 1935, Serial No. 56,439

6 Claims. (Cl. 264—3)

This invention relates to improvements in engine governors, and more particularly to speed responsive control units adapted for use with internal combustion engines, being peculiarly suited to engines of solid-injection types, such as Diesels.

An object of the invention, generally stated, is attained in a governor for the purpose noted, and which is characterized by an improved degree 10 of response to relatively smaller fluctuations in engine speed, substantially throughout the predetermined speed range through which the governor is required to operate for regulation, for example, of the fuel supply of the associated engine.

An additional important object of the present invention, when embodied in a centrifugal governor of a type in which the weights are opposed by spring loading, is to provide a closely predetermined variation of the effective spring rate, as the spring loading is varied to change the speed setting of the governor and the engine with which it is associated.

A further object of the invention is attained in an improved governor assembly for use particularly on internal combustion engines and which exhibits an improved degree of fuel supply regulation, within the lower ranges of governor controlled speeds, and which possesses a considerably improved nicety of regulation in the ranges of speed through which solid injection engines have been heretofore governor controlled only with difficulty.

Yet another object of the invention is attained in an improved arrangement of the operative connections and control elements of the governor assembly, such as to minimize inertia effects and the usual effects of friction at rest, heretofore operating against a satisfactory response of the governor to minor fluctuations in engine speed.

A still further object of the invention is attained in an improved arrangement of governor springs, embodying at least two springs of differential loading, together with means for varying the loading of one, preferably the more heavily loaded or main spring, in such a manner as to attain through a manual control element, a variation of the effective spring rate and a finer degree of regulation of governor spring loading, than heretofore possible with conventional devices.

The foregoing and numerous other objects will more clearly appear from the following detailed 55 description of preferred embodiments of the in-

vention, considered in connection with the accompanying drawings, in which:

Fig. 1 is an end elevation of an engine, particularly the governor end thereof, and the governor housing, drawn to a relatively reduced 5 scale, on which is shown a manual control lever utilized to effect speed regulation of the engine through the governor; Fig. 2 is a vertical sectional elevation through the housing appearing in Fig. 1, and illustrating a governor assembly 10 of a design in accordance with the present invention; Fig. 3 is a generally vertical sectional elevation of the assembly as viewed along the staggered section indicated by line 3—3 of Fig. 2; Fig. 4 is a section taken transversely of the assembly of Fig. 2, and as viewed along line 4—4 thereof; Fig. 5 is a transverse sectional elevation showing particularly the governor bracket, centrifugal elements, drive gear and fuel control connection, as viewed along line 5—5 of Fig. 2; Fig. 6 is a detail of portions of the connection 15 from the governor to a fuel control rod, as viewed along line 6—6 of Fig. 5; Fig. 7 is a fragmentary 20 sectional elevation of a portion of the connection from the governor to the engine fuel control organization, as viewed along line 7—7 of Fig. 5; Fig. 8 is a side elevation, showing certain 25 elements in section, of a fuel or injection pump and drive therefor as adapted for use with and control by the governor organization of the preceding figures, and as viewed from line 8—8 of Fig. 3; Fig. 9 is a vertical sectional elevation of 30 portions of the assembly illustrating a modified arrangement of the centrifugal elements and portions of the connection therefrom to one of the 35 governor springs; Fig. 10 is a horizontal sectional elevation of the device appearing in Fig. 9, and as viewed along line 10—10 thereof, and Fig. 11 is a fragmentary view illustrating further details 40 of the modification shown by Fig. 9, and as viewed from line 11—11 of Fig. 9.

Referring first to Fig. 2, the governor assembly is conveniently located adjacent to, and driven by an engine shaft, such as camshaft 15, to which is keyed or otherwise secured, a governor drive 45 gear 16, enmeshing with an angularly related governor gear 17, the latter being shown as characterized by teeth of a helical or related type to permit the angular disposition of the gears as shown. The assembly is by preference, disposed 50 within an enclosure or housing, formed in two portions, the lower of which is characterized by walls 20 which may be detachably carried by an end portion 21 of the engine frame, and may be utilized as an oil reservoir to permit of splash 55

oiling the gears and other movable elements of the assembly. The enclosure of the parts is completed by an outer wall 22, and a removable cover 23, the latter seating on and mating with the portion 20 so as to form a substantially oil-tight and dust-proof housing for the movable governor parts.

Within the housing 20 is a mounting bracket 24, secured as by stud bolts 25 to the engine frame 21, or other convenient anchorage. The bracket 24 is characterized by a substantially cylindrical portion closed at its outer end as by a plate 26 assembled as a head to the cylindrical portion, by screws 27. Projecting endwise from the cylindrical portion of the bracket, is an arm 28, at the outer end of which is a bearing portion 29 serving the purposes hereinafter described. The cylindrical portion of the bracket 24 serves to hold a pair of spaced bearings, illustrated as of anti-friction, particularly ball type, and indicated at 32. These are shown as located to engage journal portions 33 on a governor shaft 34, to which is secured the gear 17 so as to be driven thereby. The shaft 34 is positioned against endwise movement by a threaded collar 35, and projects beyond and outwardly of the cylindrical portion of the bracket 24, to receive the gear 17. The gear 17, besides being a driven element, also serves as a rotary pivot bracket for a pair of governor weights 36 and 37, each of somewhat semi-cylindrical form, and provided with ears 38 and 39 (Fig. 5), engaged by pivots 42 and 43 through which the weights are secured to the gear 17.

Within the confines of the weights is located an antifriction, preferably ball type, bearing 44, in the nature of a thrust bearing, the inner race thereof occupying a reduced portion on one end of a governor sleeve, later described, and the outer ball race being engaged by camming elements respectively formed on or carried by the weights, one thereof being shown at 48, associated with the weight 36.

The ball bearing assembly shown at 44, rather than being positioned directly on the shaft 34, is carried by a reduced portion of an axially movable but non-rotatable sleeve 50, the outer or left hand end (Fig. 2) of which is reduced as at 51, to receive and conform to a cap element 55 to which it is secured, the latter serving with other elements as will appear, to translate the axial movement of sleeve 50, to the spring mechanism and to the engine fuel assembly or other organization to be controlled.

Extending transversely through the cap 55 is a pivot pin 56, freely movable about its axis through the bore therefor in the cap, and provided with projecting, reduced, flattened ends 57. The latter extend into and operatively engage the opposite furcations 60, collectively constituting the shorter arm of a bell crank lever, the opposite or longer arm of which is indicated at 61. The furcations or arms 60 are slotted as at 62, the flattened sides of the projections 57 of pin 56, permitting these trunnion portions to enter and work along the slots 62. The bell crank lever is provided with a fixed pivot 64, mounted in the end portion indicated generally at 29, of the governor bracket 24.

The longer arm 61 of the bell crank lever 60-61 is provided with a projection or pin 68 (Fig. 6), characterized by an enlargement 69 which may, if desired, consist of a roller on the pin 68. The portion 69 occupies a lateral recess 78 in a reciprocally movable control rod or member 71, this rod element being guidedly positioned

in a tubular guide or bushing 75, conveniently threaded into and through the engine frame or back wall of the governor case 21, the threaded connection being shown at 76 and including a jam nut 77. The bushing 75 is characterized by a reduced end 80 serving to receive and support a spring 81, which may for the present purpose be regarded as an auxiliary governor spring. This element is preferably of compression type, and has an outer abutment shown as a collar 82 secured as by cotter key 83, to the rod 71.

For purposes of connection to the engine fuel control organization, a suitable example of which is hereinafter described, there is shown an arm 85 (Fig. 5) apertured at one end for securedment to the rod 71, to which it is assembled as by nut 86. The opposite end of the arm 85 is furcated, and the furcations thereof slotted as at 87 and serve to receive trunnions or projections 88 carried, for example, by an injection pump control rod or rack 90, (Figs. 5 and 8).

Although the operation of the governor and associated elements as thus far described is thought to be apparent from the description of parts and their assembly, it may be mentioned for completeness that rotation of the gear 16 during operation of the engine, imparts, in the device disclosed, movement to gear 17 at a substantially increased rate; this gear being secured to shaft 34 and the latter being positioned against substantially axial movement, rotation of the gear 17 carrying weights 36 and 37 will result in their outward displacement under centrifugal influence. This movement of the weights results in a camming action of projections 48 and 49 against the ball bearing assembly 44, in a manner tending to displace the sleeve 50 to the left (Fig. 2) and therewith the cap element 55 and the forked ends of the bell crank lever 60-61. This control movement of the bell crank lever will be in a clockwise direction (Fig. 5) about the pivot 64, and as will appear from a comparison of Figs. 5 and 6, will result in a displacement of the rod 71 to the left (Fig. 6) against the loading of spring 81. This endwise or reciprocal movement of the rod 71 will result in a similar displacement of the injection pump control rack or rod 90, in a manner to govern the displacement of fuel through, for example, the fuel pump indicated generally at 95. The pump 95 is of known type, and forming of itself no part of the present invention, need not be here described in detail. For completeness it may be noted that the cam-shaft 15 serves to carry pump cams 96 cooperating with a roller 97 of a follower 98, the latter being pivoted on an eccentric 100 susceptible of adjustment as through an eccentric shaft 105. The pump proper 95 is characterized by a pump body to which the numeral is applied, and a mounting flange 106. The displacement element or plunger of the pump is actuated as by a roller 109 carried outwardly of the pump body, either by the plunger or the plunger-following member 110. A fuel discharge or injection tube is shown at 111, through which in a well known manner, the fuel is delivered to an injector in one of the cylinders of the engine.

In the arrangement of parts and operation of the device as thus far described, it is preferred that the sleeve 50 and the cap structure 55, which are preferably secured together, be non-rotatable, and to the end of providing positively against their rotation, the cap structure is provided with a projection or pin 115 (Fig. 7) engaging a slotted guide 116 therefor in the body of the bell crank 75

lever 60—61, and so precludes the cap and sleeve from rotation with the shaft 34.

It will be understood that the parts thus far described represent a completely operative organization, except for a provision of control of the speed setting or range in which the governor control is desired. Otherwise expressed, the spring 81 will, if of adequate loading, serve so to oppose the centrifugal effect of the weight elements of 10 the governor that the assembly will function as a single spring unit, but without provision for changing the spring loading and hence the speed setting of the assembly.

In connection with the mechanism affording a 15 speed regulation of the governor through variation of its spring loading, there is provided in the portion 29 of the bracket 24, a pair of horizontal bearing pin apertures 120, through which extends a lever fulcrum pin 121, and on which is journaled, preferably through antifriction bearings 20 and by further preference, through a needle type bearing 122, a lever indicated generally at 123. The lever is accordingly movable about the pin 121 as a fixed axis. The lever 123 is preferably 25 of U shaped or channel section, being characterized by longitudinal flanges 124, and provided through a zone inwardly of its pivoted end, with a pair of spaced projections 125 apertured to receive a pin 126 on which is journalled, as through 30 antifriction bearings preferably of needle type, a roller 127, the projections 125, pin 126 and roller 127 being disposed so that the roller engages the end face of the cap 55 substantially along a prolongation of the axis of shaft 34. The opposite 35 or free end of the lever is furcated or slotted as at 130 (Fig. 4), the furcations being bridged by a spring anchorage pin 131, serving to receive a hook end of the main governor spring 132. This spring is, by preference, of tension type, and of 40 somewhat greater size and loading than the compression spring 81 heretofore described. The opposite or outer end of the spring 132 is provided with a hook end serving to engage a pin 133. For adjustment purposes the pin 133 forms part of 45 what may be considered an adjustable crank structure, and is connected as through a link portion 134 to a shaft or shank 135, the latter being adjustably secured in a clamping end 136, normally secured as by a screw 137 in tightly embracing relation to the pin 135. It will appear 50 that by releasing the screw 137, the pin 133 may be rotated about 135 as an axis, to vary the length and hence the loading of spring 132, following 55 which the screw 137 is again threaded up to maintain the predetermined adjustment.

The outer main spring anchorage just described, is carried at the free end of a swingable or pivoted adjustment arm 140 (Figs. 2 and 4), the inner end of the arm being provided with a 60 split clamp end 141, normally tightly secured in embracing relation to a short shaft 142 as by a clamp screw 143. As will best appear from Fig. 4, the shaft 142 extends depthwise of the governor housing 20—21—23, being journalled at 65 one end in a recessed boss 144 in one side of the housing, and projecting through a similar journaling portion 145 in the opposite or front wall of the case, beyond which the shaft is engaged by a swingable control lever 146 provided with 70 a split clamping end 147 and screw 150 through which the control lever is secured to the shaft. The outer end of the control lever 146 is provided with a bored, partially tapped angular offset 151, and a valve type handle 152, the threaded shank 153 of which engages the threads in 75

the bore of part 151. The inner end of the shank 153 projects beyond the offset portion toward the front wall of the case, where it abuts a bevelled clamping surface 154. It will be obvious from this arrangement that after the manual control arm 146 is disposed in its desired setting, threading up of the shank 153 will effect a frictional securement of the arm 146, in its adjusted position. It is contemplated, as will appear from Fig. 1, that the arm 146 be movable through a range say 10 of 90 degrees, and that suitable indicia 155—156 be provided to indicate to the operator the effect of movement of the control arm 146 to different positions. This indicia may obviously take the form of numerical indications of engine speed 15 resulting from the various control placements of the arm.

The inner end of shaft 142 is provided with an angular adjustable crank or lever 160, including a split clamping portion 161 serving with a screw 162 to enable a tight frictional securement of the element 160 to the shaft 142. Pivotally connected, as through a pin 164 to the element 160, is a link 165, the opposite end of which is pivotally connected as through a pin 166, to an adjustable extension arm or crank 167, to the eccentric shaft 105. The latter serves, as of itself is well known, through rotation of the eccentric 100, to shift the follower 98 laterally, or to the right or left as it appears in Fig. 8, thus moving the roller 97 to the right or left of the axis of the cam-shaft 15, hence effecting an early and late adjustment of injection timing.

The function and advantages of the main 35 spring and connections to the remainder of the governor assembly, are thought to be apparent from the foregoing description of parts but it may be noted that, assuming the spring 132 to occupy an approximately right angular relation to the lever 123, the spring will, for a given adjustment of the crank 133, exert a maximum effective loading on the outer end of the lever 123. Otherwise expressed, this main spring will for a given loading adjustment, exert its maximum pull 40 when approximately parallel to the governor 45 shaft 34. This loading, as will be obvious from the drawings, will be in a direction to oppose the centrifugal effect of weights 36 and 37. It will further appear that the movement of the manual control lever 146 in a counterclockwise direction 50 (Figs. 1 and 2), will reduce the angularity of the axis of spring 132 with respect to the lever, so that, as the lever is brought to an end position indicated by dotted lines (Fig. 2), the spring 55 then being beyond the axis of the lever, the loading of the spring on the lever vanishes. There is thus provided an exact and extremely responsive facility for varying the effective spring loading on the governor weights.

However, in order to insure a still closer degree 60 of governor speed regulation, it will be noted that arm 140, movable about shaft 142, has such axis displaced appreciably from the point of anchorage of spring 132, to the lever 124. It results 65 from this fact that, irrespective of the angularity of the spring to the lever, its effective length and hence its loading are decreased as the outer end of the spring, through levers 140 and 146, are moved anticlockwise. This fact will be apparent 70 from a comparison of the full line and dotted positions of the outer end of the spring 132. It will further be noted that the spring loading on the governor, in utilizing the dual spring arrangement disclosed, never vanishes completely, since the auxiliary spring 81 remains at all times in 75

loading relation to the governor weights. It is nevertheless rendered possible to vary, with increasing exactitude, the resultant loading of the two springs, particularly through the means for 5 concurrently changing the angle and the absolute loading of the main spring 132.

From the foregoing description it will appear that the adjustment features of the mechanism permit a precision control and simultaneous variation of both the effective spring loading, and the effective spring rate, opposing the centrifugal force of the governor weights operating in a direction axially of the governor. It will be seen that when the main spring 132 is in its full speed 10 position, or at substantially a right angle to the governor lever 123, the spring loading or tension is at a maximum, and its component, parallel to the line of the opposing axial force due to the effect of the governor weights, is also at a maximum. While the spring is in this position, a small movement of the pin 131 at the outer end 15 of the governor lever 123, such as may be due to a slight change of engine speed, results in a direct pull on the spring, and hence results in a substantial change of spring force, so that the effective spring rate is at a maximum. When, however, the spring 132 occupies its idling or low speed position as shown by dotted lines (Fig. 2), the tension of spring 132 is at a minimum, and its 20 component parallel to the line of governor force, is practically zero, with the result that the effective spring force is also practically zero, only the auxiliary spring 81 having at this time any substantial effect. It will be noted that any motion 25 of the pin 131 at the free end of the governor lever occurs at nearly a right angle to the axis of the main spring 132 when in idling position, and hence results in a practically negligible change of the loading of this spring, with the result that the effective spring rate is, under these 30 circumstances, practically zero. There is thus provided an ideal condition involving a decreasingly effective spring rate, as the effective spring force or speed setting is decreased, giving a nearly constant speed regulation over the predetermined 35 range of speed settings.

It is further possible by varying the eccentricity of the fulcrum 142 on which the spring lever 140 is pivoted, relative to the pin 131 at the end of the governor lever 123, to vary the amount by which the effective spring force varies for a given variation of the spring rate. By increasing this eccentricity, the spring force is made to vary more rapidly relatively to the variation of the spring 50 rate, since the effective spring rate depends only on the angle between the axis of the spring, and the line of force due to the centrifugal effect of the governor weights. It is noted that the effective spring rate is independent of the spring loading.

It will further appear that the provision of the variable spring anchorage 133—135 at the outer end of lever 140, provides a means permitting a variation of the spring loading, which may be availed of in any angular position of the spring, without influencing the spring rate.

There is shown by Figs. 9, 10 and 11, a modification or alternate form of connection between an axially displaceable governor sleeve, and the fuel supply control organization. In the structure according to these figures, the governor shaft 170 is supported in a plurality of spaced antifriction bearings, one of which is indicated at 171 and carried within a bracket 172 which is or may be substantially identical with the bracket 24. An

enlargement 173 is provided on shaft 170, adjacent which the governor gear 174 is located and suitably secured to the shaft. The governor gear 174 similar to gear 17, constitutes a bracket for governor weights 175 and 176, provided with pins 177 and 178, and sleeve-camming projections 180. In this arrangement the camming effect due to the outward movement of the governor weights, serves to displace, axially of the shaft, a sleeve 181 which may be rotatably secured to, but is 10 axially movable along the shaft 170. The sleeve 181 operates adjacent the gear 174, and there is provided on a shouldered portion of the sleeve, a wearing ring 182. The outer end of the sleeve 181 is reduced or shouldered to receive an anti-friction bearing assembly 183, the outer race of which serves to carry a partly conical element 184. Spaced parallel projections 185 (Fig. 10) are provided on the cone shaped piece 184, these projections serving to receive therebetween a conforming projection 186 on the lever 187, the portion 186 being provided with a headed insert or pin 190 serving as a wearing element disposed axially of the cone-shaped element 184 and in line with the axis of shaft 170. The main spring arrangement, and connections therefrom to lever 187 are or may be identical with those shown by Figs. 2 and 4 and hence need not be presently described. Obviously the cone-shaped element 184 is held against rotation by the manner of its engagement with the lever 187.

As a means for utilizing for control purposes, the axial movement of the cone-shaped part 184 resulting from a similar displacement of the sleeve 181, there is provided a lever 191 movable 35 about a fixed pivot pin 192 and provided on its governor end with a roller 193 secured as by a pin 194 to the short end of the lever 191. The free end of the long arm of the lever 191, is provided with an adjustable, threaded and headed pin 195, the position of which with respect to arm 191 is adjustable as through a lock nut 196. The headed portion of the screw 195 engages a roller 200 carried as by a pin 201 in the furcated end 202 of the reciprocable fuel control rod 203. The 40 spring 204 may be a counterpart of spring 81, heretofore described, and the manner of connection from the reciprocable member 203 to a fuel supply control element such as 90, may be substantially the same as heretofore described. In 45 the modified construction, a governor bracket 172 (Fig. 11) serves a purpose generally similar to the bracket 24, heretofore described, and includes an extension arm 206 and a terminal, transversely bored member 207 providing a support for the 50 pivot 208 for lever 187. Forwardly of the portion 207 is an apertured lug 210, vertically bored and serving to receive and conform to a squared shank 211 on the pivot 192 for lever 191. The pin 192 is of circular section above the squared shank, so as to provide the requisite pivot portion. Securement of the pin 211—192 is conveniently effected as by an assembly nut 212.

From the foregoing it will appear that outward movement, or shift in position to the left (Fig. 65 10), of the partly cone-shaped piece 184, will tend to displace the lever 191 about its pivot 192 in an anticlockwise direction (Fig. 10) in a manner to move the reciprocable rod 203 against the loading of spring 204. Since the remaining portions of the assembly are or may be identical with those heretofore described, no repetition of such description is regarded as necessary. The arrangement is such that the length of the lever 191 between pivot 192 and pin 184 is less than 70 75

between pivot 192 and pin 195 so that there results, as in the preceding construction, a motion-multiplying connection from the governor actuated sleeve, to the reciprocable control rod governing the engine fuel supply or other organization to be controlled.

It will be apparent from the foregoing description that due to the facilities for effecting a close adjustment and regulation of both the actual and effective loading and spring rate of the main governor spring, and also due to the minimization of internal friction and hence of friction at rest, the assembly described will materially improve the degree of engine fuel and speed regulation here-
10 tofore attainable with governors intended for similar types of service; further that the device described attains in every particular, each of the several objects hereinbefore expressed and implied.

20 The detail of present disclosure of preferred embodiments of the invention, is to be understood solely in a descriptive, and not in a limiting sense, since numerous changes may be made in the parts as well as in their combinations and
25 arrangements, without departing from the full intended scope of the invention as defined by the claims hereunto appended.

I claim as my invention:

1. In a governor assembly of a type including
30 centrifugally movable speed responsive members, a governor shaft and means for rotating said shaft to actuate said members, an element displaceable along the axis of the shaft in response to movement of the centrifugal members, a lever operatively associated with the displaceable element, a spring connected to the lever in a manner to oppose speed responsive movements thereof, a manual control member for swinging said spring to vary the angle and effective loading
35 thereof with respect to the lever, and through a range of positions including both zero degrees and ninety degrees to the lever, an auxiliary spring of substantially constant effective loading on the centrifugal members, and means for varying the inherent loading of the spring, in the different positions of the control member.

2. In a governor assembly of a type including centrifugally movable speed responsive members, a governor shaft and means for rotating said shaft to actuate said members, an element displaceable along the axis of the shaft in response to movement of the centrifugal members, a lever operatively associated with the displaceable element, a tension spring connected at one of its
50 ends to the lever and normally tending to oppose its speed responsive movement, a manually movable control arm connected to the opposite end of the spring, and pivoted so as to vary the effective loading of the spring incident to its movement, a connection between the last said end of the spring and said arm, adapted to permit an adjustment of spring loading in any position of the arm, an auxiliary spring and connections therefrom such that it tends to oppose the speed
55 responsive movement of the centrifugal members, and means for selectively disposing the control arm in positions such that the tension spring serves respectively to oppose, to augment, and to be without effect on the effective loading
60 of the auxiliary spring.

3. In an engine governor assembly, a plurality of centrifugally movable speed responsive members, a governor shaft, means for rotating said shaft to actuate said members, an element displaceable axially of the shaft in response to cen-

trifugal displacement of said members, connections for translating the movements of said element to an engine organization to be controlled thereby, a pair of governor springs connected in opposing relation to centrifugal movement of the axially displaceable element, and in a manner to impress thereon an effective resultant spring loading and means for varying the angular position of one of said springs, to provide a loading component variable between zero and the maximum inherent in the spring, and independently of the other spring, constituting a substantially constant loading component, for controlling the spring loading against the centrifugal governor elements.

4. In an engine governor assembly, a plurality of centrifugally movable speed responsive members, a governor shaft, means for rotating said shaft to actuate said members, an element displaceable axially of the shaft in response to centrifugal effect of said members, connections for translating movements of said element to an engine organization to be controlled thereby, a pair of governor springs, one of relatively greater, and the other of substantially lesser loading, separate connections whereby the springs are functionally related in opposing relation to the axially displaceable element, one of said springs being of constant loading, and the other of variable loading, and means for manually varying the angular position, and thereby the effective loading of the latter spring, between angular limits including a zero loading, and a maximum loading position of the spring substantially parallel to the governor shaft.

5. In an engine governor assembly, a plurality of centrifugally movable speed responsive members, a governor shaft, means for rotating said shaft to actuate said members, an element displaceable axially of the shaft in response to centrifugal displacement of said members, connections, including a governor lever, for translating the movements of said element to an engine organization to be controlled thereby, a main governor spring and an auxiliary governor spring, means including the governor lever, connecting said springs in opposing relation to the axially displaceable element, and manually controlled means for varying the angular relation of the main spring to the lever, whereby to vary the effective total spring loading on the centrifugally movable members, the last means being arranged to permit movement of the main spring from a maximum lever-loading position substantially parallel to the governor shaft, through a position corresponding to zero loading of the lever by the main spring.

6. In a governor assembly, a plurality of centrifugal governor weights, a governor shaft, powered means for rotating the shaft to actuate said weights, a sleeve on one end of the shaft movable axially thereof in response to centrifugal weight movement, a bell crank lever having a shorter arm pivotally connected to said sleeve, a fixed lever pivot, and a longer arm, a control rod disposed at substantially a right angle to the governor shaft and pivotally related to the longer bell crank arm, a compression spring of substantially constant loading carried by the control rod, and so related thereto as to oppose centrifugal movement of the governor weights through said crank and sleeve, a control connection from said rod, a bracket in which the governor shaft is journaled, a governor lever pivotally related to said bracket, a roller on said lever provided

with antifriction bearings, and normally engaging a portion of the sleeve, a main governor spring of tension type, having one of its ends secured near the free end of said lever, a pivoted arm, an adjustable anchorage of eccentric type at the outer end of said arm to the opposite end of the main spring, and a manual control lever

arranged for swinging said arm about its pivot in a manner to vary the angle and effective loading of the main spring through a range embracing zero and maximum effective loading of the main spring on the governor lever.
